UNITED STATES PATENT OFFICE.

WILLIAM L. RATHJEN, OF PORTLAND, OREGON.

THREAD HOLDER AND CUTTER.

Application filed July 12, 1927. Serial No. 205,114.

This invention relates generally to spools for holding thread, and particularly to a device for holding the thread on the spool and for cutting off pieces of thread.

5 The first object of this invention is to provide an exceedingly simple and efficient form of thread cutter and holder by means of which a piece of thread can be easily cut from a spool and the remaining end on the 10 spool be securely held in place for later use.

The second object is to provide a means for preventing the undue soiling of thread and loss of time occasioned by same becoming unwound in work boxes or on racks when 15 the end has become freed.

The third object is to prevent the rolling of the spool on the table or floor to the inconvenience of the user.

The fourth object is to so construct the 20 device that it can be manufactured at a negligible cost and easily applied or transferred from one spool to another without the use of any tools or requiring any special skill in the operation.

25 These, and other objects, will become more apparent from the specification following as illustrated in the accompanying drawing, in which:

Figure 1 is a side elevation of a spool 30 showing the device attached thereto with portions of the ends of the spool and of the device broken away in section. Figure 2 is an end elevation of Figure 1. Figure 3 is a side elevation of Figure 1. Figure 4 is 35 a transverse section taken along the line 4-4 in Figure 3 showing the first stop in the operation of cutting off a piece of thread showing the thread being pulled to the required length. Figure 5 is similar to Figure 4 showing the thread being cut. Figure 6 is similar to Figure 5 showing the thread severed with the remaining end held in the cutting notch.

Similar numbers of reference refer to similar parts throughout the several views.

Referring in detail to the drawing, there is illustrated the ordinary wooden spool 10 whose flanges 11 are ordinarily provided with a notch for the purpose of holding thread, but which in this instance is not required. Thread 12 is shown wound on the spool. The spool 10 is also provided with the usual hole 13 passing through its longitudinal axis.

Turning now to the device itself it will 45 be seen to consist of a somewhat U-shaped

frame of thin spring metal whose central portion 14 is curved to allow same to bear against the surface of the thread 12. The member 14 curves outward to form the projections 15 at each end of the spool. This 60 provides clearance for the flanges 11, adds spring to the part and prevents the spool from rolling on an inclined surface.

The sides 16 of the device are parallel and are provided with the dished ends 17 adapted 65 to snap into the opening 13 of the spool. The member 14 is provided with a pair of opposite V notches 18 which have a double function; first that of cutting the thread to the desired length, and second the holding 70 of the remaining end against unwinding.

The operation of the device is as follows: To place same on the spool it is merely pressed against the side of the flanges 11 so as to spring the sides 16 apart sufficiently 75 far to allow the spool to enter. The end of the thread is then pulled out to the desired length and then drawn across the notch 18 with sufficient force to sever the thread, where the end remains as above suggested. 80

The only object in providing two notches 18 is to render it immaterial which way the device is placed upon the spool, it being only necessary to have a notch into which the thread can be drawn by a movement which 85 would unwind the thread.

I am aware that spools have long been provided with notches in the flanges for holding the thread against unwinding, but it is a matter of common knowledge that such 90 means are not dependable for the object intended and are constantly breaking away and becoming useless; I therefore do not intend to cover such devices broadly, but I do intend to cover all such forms and modifications 95 thereof as fall fairly within the appended claims.

I claim:

1. A thread holder and cutter consisting of a U-shaped spring metal clip having trunnions formed in its ends adapted to engage the hole ends of a spool; and having a cutting edge on the side of the middle portion of said clip, the flat side of said middle portion bearing against the thread on the spool upon 100 which the device is mounted.

2. A thread holder and cutter consisting of a U-shaped spring metal clip having trunnions formed at each end between which a spool can be rotatably mounted; the mid por- 110

tion of said clip having a curvature which will cause same to bear tangentially against the thread wound on said spool.

3. A thread holder and cutter consisting of a U-shaped spring metal clip having trunnions formed between its ends between which a spool can be mounted and having a curved

middle portion adapted to cause same to bear tangentially against the thread wound on said spool, said curved portion having cutting notches formed therein; and having its ends projecting radially beyond the spool flanges to prevent same from rolling.

WILLIAM L. RATHJEN.
